UNITED STATES PATENT OFFICE.

CARL R. WINTER, OF CINCINNATI, OHIO.

LIFTING-JACK.

1,365,758.

Specification of Letters Patent. Patented Jan. 18, 1921.

Application filed September 20, 1917. Serial No. 192,253.

To all whom it may concern:

Be it known that I, CARL R. WINTER, a citizen of the United States, and a resident of Cincinnati, in the county of Hamilton and State of Ohio, have invented certain new and useful Improvements in Lifting-Jacks, of which the following is a full, clear, and exact description, reference being had to the accompanying drawings, forming 10 part of this specification.

My invention relates to lifting jacks for automobiles and the like wherein the jack is permanently secured to the automobile and operable from some convenient point of 15 the machine, without the necessity of troublesome labor in connection therewith. I am aware that it has been proposed in the past to provide permanent jacks on automobiles, and other devices such as lifting trucks 20 and the like, but so far as I have been informed, these devices, when applied to automobiles have been too cumbersome, expensive and unwieldy to have come into practical use.

25 In permanent lifting jacks for automobiles, beside the above defects, there has been another defect which applies to all jacks for automobiles, so far as I am informed. This is, that the thrust for lifting is applied 30 on a straight line from the ground to the load supporting plate, and hence the supporting surface on the ground must be fairly level, or else the vehicle will be thrust forward and topple the jack over, due to the 35 slanting of the base. Thus it is that in jacking up the rear wheels of an automobile on the road, much difficulty is frequently found in getting the proper support for the jack.

40 It is the object of my invention to provide a jack which has a pivoted foot for supporting the load, thereby providing a jack which is enabled to give at the pivot so as to allow for unevenness of the base. The 45 importance of this method of elevating the load is apparent when applied to a permanently attached jack, because in it the selection of a proper supporting surface for the jack would be a good deal of difficulty on a 50 rough road.

Then again, I provide a double toggle lift which permits me to do away with the necessity of demanding a space for the lifting column above the chassis of the automobile, 55 as in the usual type of jack, as will be apparent from the description that follows.

The objects and advantages above stated, and others that will appear below, I accomplish by that certain construction and arrangement of parts to be hereinafter more 60 specifically pointed out and claimed.

In the drawings,

Figure 1 is a side elevation of the rear portion of an automobile, showing my invention applied to the rear axle, with the 65 wheel and axle broken away to expose the jack.

Fig. 2 is a top plan view of the same parts shown in Fig. 1, partly diagrammatic.

Fig. 3 is a side elevation of the jack on a 70 larger scale as provided for attachment to a rear axle.

Fig. 4 is a rear elevation of the jack.

Fig. 5 is a vertical section through one of 75 the sockets.

Fig. 6 is a section of the foot and a projection therefrom.

It should not be understood, from the fact that the jack shown in the drawings and described below is applied to the rear 80 axle of a vehicle, that this is the only manner in which its use is contemplated. On the contrary, with simple modifications of the mounting structure the jack could be applied to other positions and other vehicles, 85 although it is particularly well adapted to automobiles.

The vehicle to which the device is shown as applied has a rear axle 1 and rear wheels 2. As usual there are mud guards 3 and a 90 running board 4.

The housing for mounting the jack on the rear axle is shaped to conform to the axle and comprises a simple clamp or clip, having an upper member 5, lower member 6 95 and securing bolts 7. The lower member has pivoted to it the toggle arms 8, 8, 9, 9, said arms being in pairs, preferably to give additional strength (Fig. 4). The pivotal mounting is preferably made by securing a 100 pin 9^a through the clip member and mounting the arms on the two exposed ends of the pins.

The jack has a coupling member 10 to which are pivoted at each side the pairs of 105 toggle arms 11, 11, 12, 12. To the member 10 is pivoted in any suitable manner the supporting foot 10^a. The arms 8, 8, and 11, 11, are pivotally connected to a socket member 13, and the arms 9, 9, and 12, 12, are 110 likewise connected to a socket member 14. The two socket members are alike, and have

ears 15 which provide a mounting for the pivot pins 16 by means of which the toggle arms are pivoted. It can thus be seen that a double toggle device is provided, mounted 5 on the axle and with a supporting foot adapted to be thrust downward against the ground by the operation of the toggles.

For this purpose, the socket members are 10 interiorly screwthreaded and an operating screw 17 provided with oppositely directed threads, as in a turn buckle screw, so that when in engagement with the socket members the operation of the screw will draw the socket pieces toward, or force them 15 away from each other. The operation of drawing the sockets toward each other thrusts down the supporting foot, as will be readily understood. To prevent the toggles from getting in parallel with each other and 20 thereby permitting the load to swing down, bosses 6^a are formed on each side of the clip member, and bosses 10^b on each side of the member 10, which serve as abutments to prevent the toggles from assuming such position.

For operating the screw, a shaft 18 is provided, having a universal joint connection 19 with the screw, the same having a sliding connection 19^a with the shaft. The shaft 18 enters a small bevel gear housing 20, and is provided with a beveled gear 21 in said housing. Mounted beneath the running board on the car is a shaft 22, which is turned by a removable operating handle 23. The 35 shaft 22 enters the housing 20 also and has a beveled gear 24 within said housing which meshes with the gear 21. The housing is such that its movement around the shaft 22 will maintain the beveled gear 21 always 40 equidistant from the axis of said shaft.

The pivoted foot which is preferred by me is of the ball and socket type, which permits of some freedom of the foot for adjustment of its positions in any direction. This is 45 particularly valuable in the toggle type of jack which I have developed, since without it the operating screw would probably jam tight, should an uneven surface be encountered.

50 The member to which the toggles are pivoted is formed with a semispherical recess 25 on the under side. The foot is shaped into a ball 26 on its upper side, which ball fits into the recess. A bolt 27 is secured in the toggle 55 pivot member 10, which passes through the foot. A conical or tapering recess 28 in the upper side of the foot permits the movement of the foot on the bolt, and the head 29 of the bolt seats against a tapered boss 30 in a 60 recessed portion of the under side of the foot, which also permits of the tipping of the foot with regard to the bolt.

The above familiar construction provides

a simple method of operating the screw and hence the jack. It can be worked quickly 65 and conveniently, and is of quite simple construction. It is not desired that the claims that follow be limited in their construction due to the fact that I have failed to call attention during the above description to the 70 possibility of substitution of equivalent structures without departing from the spirit of my invention.

Having thus described my invention, what I claim as new and desire to secure by Letters Patent, is:—

1. The combination with a securing clip for mounting on a vehicle, a double pair of toggles secured to said clip, said toggles having interiorly threaded socket members 80 for their middle joint, a screw passing through said socket members and having oppositely threaded ends for engagement therewith to actuate the toggles, a coupling member for the outer ends of the toggles 85 with a supporting foot pivoted thereto whereby said screw may maintain a substantially horizontal position, a shaft mounted on the vehicle, and having flexible connection with the screw, and means for revolving said shaft.

2. The combination, in a jack, of a double toggle, a foot at one end of the double toggle, means for suspending the other end of said toggle from a vehicle, a screw for engagement with the middle joints of the double toggle, a revoluble shaft on the vehicle, an extendable shaft operatively connected thereto, and having a swinging connection therewith, and a universal joint between the latter shaft and the screw, for the purpose described.

3. A jack for vehicles and the like comprising a member to be secured to the automobile, and a supporting foot, toggles connecting said member and foot, means for drawing the middle joints of the toggles toward and away from each other to depress or elevate the foot, comprising a right and left hand screw and means at the two extremities of the toggles for preventing the toggles from being drawn past a parallel with each other, for the purpose described.

4. The combination with a securing clip for mounting on a vehicle, a pair of toggles secured to said clip, said toggles having interiorly threaded socket members for their middle joint, a screw passing through said socket members and having oppositely threaded ends for engagement therewith to 115 actuate the toggles, and a supporting foot secured to the toggles, said clip and foot having means for preventing the toggles from moving past a parallel with each other, for the purpose described.

CARL R. WINTER.
